G. I. DICKEY

TENT

Filed Nov. 17, 1923

UNITED STATES PATENT OFFICE.

GEORGE I. DICKEY, OF TOLEDO, OHIO.

TENT.

Application filed November 17, 1923. Serial No. 675,256.

To all whom it may concern:

Be it known that I, GEORGE I. DICKEY, a citizen of the United States, and a resident of Toledo, in the county of Lucas and State 5 of Ohio, have invented a new and useful Tent, which invention is fully set forth in the following specification.

My invention has for its object to provide a tent frame whereby a tent particularly of 10 the palmetto type may be easily erected and the walls suitably stretched. The invention provides a foldable means of light weight that may be easily positioned in the erection of the tent, and whereby the walls including 15 the top may be readily stretched and which dispenses with the use of a central pole as well as of end central poles for the support of the tent.

The invention may be contained in devices that vary in form. To illustrate a practical application of the invention I have selected a palmetto tent and a supporting frame containing the invention and shall describe it hereinafter. The tent selected 25 is shown in the accompanying drawings.

Fig. 1 of the drawings shows a diagonal sectional view taken through opposite corners of the tent to illustrate in a general way the proportions of the parts. Fig. 2 is a 30 horizontal sectional view and a broken view showing a wall distending means. Fig. 3 is a vertical sectional view of the parts shown in Fig. 2. Fig. 4 illustrates a socket for engaging the peak of the tent. Fig. 5 illustrates a top disk for securing stay ropes to the tent.

The tent is formed of a suitable fabric, such as canvas, that is cut and sewed together to produce a palmetto form of tent. 40 The walls 1, including the top, as well as the side walls of the tent, are stretched by a frame that may be easily positioned within the tent. The tent is provided preferably with a floor 2 also formed of suitable fabric, such as canvas. The floor 2 may be spread and if desired stretched and maintained in its position by means of straps 3 and stakes 4.

To sustain the walls of the tent, separable 50 or jointed, upright members 5 may be provided which are located in the corners of the tent. In the construction shown each upright is formed of tubular parts 6 and 7 having end portions that interfit so as to securely connect the parts in alignment. One end

of one of the parts may be swaged so as to fit one of the ends of the other part to thus produce an exceedingly light and yet very strong supporting member. The lower part of the member is securely connected in the 60 corner of the tent as by the strip 8 that is sewed to form a pocket in which the lower part 6 of the member tightly fits. This maintains the part 6 in position in the tent and makes the erection of the tent easy. All 65 that is necessary, is to set the end of the other part of the upright into the end of the lower part.

The upper ends of the uprights are connected together by means for distending the 70 upper ends of the uprights and the peak of the tent which stretches the walls of the tent and renders the tent exceedingly stable and the walls smooth and taut. The upper ends of the uprights are connected together 75 by means of links 9 that are pivotally connected. In the form of the tent shown they extend through the axis of the tent and are knife hingedly connected with the central member 10 having the arms 11. The arms 80 11 are channeled on their under sides, as at 12, and the ends of the links 9 project in the channels and are hingedly connected to the member 10 within the channels and so as to prevent any lateral movements of the links 85 relative to the member 10, or rotative movements of the member 10 relative to the links, and also to prevent the links from being raised above a certain angle with respect to the top of the member 10, or to prevent the 90 member 10 from being forced down or lowered below a certain point with respect to the outer ends of the links 9.

The links 9 may be formed of rods that may be flattened at their outer ends as at 95 13 in order to fit the channels 12 formed in the arms 11 of the central piece or part 10. The links 9 may be connected to the upper ends of the corner uprights 5 by any suitable means. In the form of construction shown 100 the links 9 are pivotally connected to cups or sockets 14 that may be readily placed over the upper ends of the uprights 5. The tops of the cups or sockets 14 is rounded to prevent penetration of the canvas that forms 105 the tent. The outer ends of the links are hingedly connected to ears located at the sides of the sockets. If, therefore, member 10 is located well above the upper ends of the uprights and the links are connected to 110

the uprights through the sockets and the member 10 is pulled down the sides of the tent may be stretched by reason of the outward movement of the corner uprights. The links thus form a double toggle whereby the walls may be stretched with considerable force as compared to the force used in drawing the part 10 downward.

In order to sustain the top and if desired to stretch the top a member may be located intermediate the part 10 and the peak. This will operate to maintain the walls of the tent in a stretched condition. In the form of construction shown an adjustable member 15 is located intermediate the part 10 and the peak. This will allow for shrinkage that might occur in case of wetting of the tent and prevent the canvas from becoming unduly permanently stretched. A screw member 15 is threaded through the part 10 and engages the peak 16 of the tent. The peak may be provided with a socket 17 that is connected to a pair of discs 18 by means of the pin or stud 19 and the nut 20 which will effectually close the peak and yet prevent tearing of the tent. The end of the screw member 15 is located in the socket 17 and when rotated will push the peak up and force the part 10 down thus causing the corners to spread and suitably spread the walls. A crank 21 may be connected to the end of the screw 15 for convenience of operation of the screw.

I have thus produced by my invention an exceedingly attractive tent and one that may be easily erected and one which will withstand winds and storms of considerable violence. The distending of the corners and the peak of the tent and consequently of the uprights of the tent will spread the cloth to form a smooth surface and thus give the tent a pleasing appearance.

The outside disc 18 may be provided with ears 23 having openings for receiving stay ropes.

I claim:

1. In a tent, a distending means having parts extending inwardly from the corners of the tent and hingedly jointed together in a central part of the tent, an element located intermediate the top of the tent and the joint for holding the joint of the parts downward by the tension of the top.

2. In a tent, a distending means having parts extending inwardly from the corners of the tent and hingedly jointed together in a central part of the tent, and an adjustable element located intermediate the top of the tent and the joint for holding the

joint of the parts downward by the tension of the top.

3. In a tent, a distending means having parts extending inwardly from the corners of the tent and hingedly jointed together in a central part of the tent and a threaded rotatable member located intermediate the top of the tent and the joint for forcing the joint downward and the top upwards and distending the corners.

4. In a tent, a distending means having parts extending inwardly from the corners of the tent and hingedly jointed together in a central part of the tent, an element located intermediate the top of the tent and the joint for holding the joint of the parts downward by the tension of the top and uprights connected to the parts at the corners of the tent.

5. In a tent, a distending means having parts extending inwardly from the corners of the tent and hingedly jointed together in a central part of the tent, a threaded rotatable member located intermediate the top of the tent and the joint for forcing the joint downward and the top upwards and uprights connected to the parts at the corners of the tent.

6. In a tent, uprights located in the corners of the tent and connected together by links hingedly jointed together in a central part of the tent and an element located intermediate the top of the tent and the joint for forcing the joint of the parts downward and stretching the sides of the tent by the tension of the top.

7. In a tent, uprights located in the corners of the tent and connected together by links hingedly jointed together in a central part of the tent and an adjustable element located intermediate the top of the tent and the joint for forcing the joint of the parts downward and stretching the sides of the tent by the tension of the top.

8. In a tent, jointed uprights located in the corners of the tent, sockets for receiving the upper ends of the uprights, links connecting the sockets and hingedly connected at the central part of the tent, a socket member located in the peak of the tent and an adjustable member located intermediate the joint of the links and the socket of the peak for stretching the walls of the tent by the pressure of the peak of the tent on the socket member.

In testimony whereof I have hereunto signed my name to this specification.

GEORGE I. DICKEY.
